UNITED STATES PATENT OFFICE

WALTER LEWIS HAWKINS, OF ST. LOUIS, MISSOURI, ASSIGNOR, BY MESNE ASSIGNMENTS, TO DURO METAL PRODUCTS COMPANY, OF CHICAGO, ILLINOIS, A CORPORATION OF ILLINOIS

SPARE-TIRE LOCK

Application filed June 21, 1928. Serial No. 287,178.

This invention relates generally to locks and, more particularly, to a certain new and useful improvement in devices especially adapted for locking against unauthorized removal certain automobile spare-parts, such, for instance, as the spare rim and tire.

My invention has for its objects the provision of a device for the purpose stated which is compact in structure, conveniently operable, and efficient in the performance of its intended functions.

And with the above and other objects in view, my invention resides in the novel features of form, construction, arrangement, and combination of parts hereinafter described and pointed out in the claims.

In the accompanying drawings,—

Figure 1 is an elevational view, partly broken away and in section, of a spare-rim and its tire, illustrating a lock of my invention operatively associated therewith and with the wheel-carrier;

Figure 2 is an enlarged sectional view of the lock, similarly shown in connection with the spare rim and its carrier; and

Figure 3 is a sectional view of the lock taken approximately on the line 3—3, Figure 2.

Referring now more in detail and by reference characters to the drawing, which illustrates a preferred embodiment of my invention, my new lock is designed for use in connection with the demountable spare-rim and its carrier. To such end, the locking-assembly includes a block A provided transversely or horizontally with a bore 1, which extends from the outer or rear face to the inner or front face of block A and in which, as best seen in Figure 2, is arranged for bodily rotatory movement a nut 2, conjoined to which adjacent its one or rear end is a collar 3 adapted for nut-retaining engagement with the outer face of the block A, as shown. Rearwardly of collar 3 and preferably integral with or otherwise rigidly conjoined to nut 2, is an actuating head 4 preferably of hexagonal or other suitable form for wrench-engagement. Formed longitudinally in the nut 2 and opening only to the inner or forward face of block A, is an internally

threaded elongated or bolt-accommodating recess 5, and formed peripherally on nut 2, is a plurality of ratchet-notches 6, two such notches being shown spaced diametrically of the nut and each having a cam face n and a shoulder n' .

Also formed in block A, is a longitudinally or vertically disposed reduced bore 7, which opens at its one or lower end into the bore 1 and at its other or upper end into an enlarged cylindrical recess 8 disposed transversely or horizontally in block A above (reference being had to Figures 2 and 3) and extending in parallelism with bore 1, recess 8, however, for purposes soon to appear, opening only on the rearward outer face of block A. Opening into the recess 8 and aligning with the bore 7, is a seat 9 for a spring 10, and disposed at an end against the spring 10 and in the bore 7, with the latter as its guide or way, is a shiftable bolt or pawl 11 adapted yieldingly, under the tension of spring 10, for engagement at its other end with the nut 2 at its respective ratchet-notches 6 for preventing rotatory movement of the nut 2 in one direction, namely, the direction faced by the shoulders n' .

In passing, I may say that the block A is preferably provided with an aligning plug-closed opening, as at 12, to facilitate placement of the spring 10 and bolt 11 in the assembling of the several parts of the lock.

Disposed in the recess 8 and pinned, as at 13, or otherwise fixed to block A against removal, is a preferably cylindrical casing 14, mounted for rotatory movement in which is a cylindrical member or barrel 15 adapted only for rotatory actuation, as is customary in such locks, by means of a key 16 insertable into the barrel 15. The barrel 15 projects forwardly within block A, and projecting from the forward end of barrel 15, is a longitudinally disposed and axially offset crank-pin 17 adapted to fit and work in a slot 18 provided in the spring-pressed bolt 11, the axial width of which slot is sufficient to permit lengthwise movement of the bolt 11 by the nut 2 in riding thereover either when key-actuated, as shortly appears, or when rotated in the di-

rection opposite to that faced by the notches 6, for purposes soon to appear.

Formed in the nut 2 adjacent the collar 3, is a circumferential recess or groove 19, with the walls of which a pin 20 driven into the block A engages to rigidly retain the nut 2, in co-operation with the collar 3, from endwise movement in or removal from the block A.

Forming part of and completing the lock, 10 is a rim-engaging member B, which includes an approximately oblong rectangular plate 21 provided marginally upon three sides with a forwardly presented flange, as at 22, and at its one or lower end 15 with a preferably integral hook-extension 23. Member B is adapted to fit at its main or plate-portion 21 flatwise against, and completely cover and conceal, the forward end face of the block A. For such purpose, the plate 21 is formed upon its rear face with a recess, as at 24, adapted to receive and accommodate a block-locating lug or boss 25 projecting from the forward face of the block A, the member B being transversely provided 20 at said recess 24 with an opening, as at 26, for a suitable headed screw 27 adapted to thread into an internally threaded recess 28 formed in said boss 25 for detachably securing the block A and member B operatively together, 25 the member B having a second opening, as at 29, adapted to register with the internally threaded recess 5 of the nut 2.

Normally, as when the key 16 is removed from the lock-barrel 15, the bolt 11 yieldingly 30 engages the nut 2 at one or the other of its notches 6 and prevents rotatory movement of nut 2 in the direction, as stated, faced by the shoulders n' or, as it might be said, in the direction that would unscrew or unfasten the 35 nut 2 from threaded engagement with a bolt fitted into its recess 5. However, by means of a wrench or other suitable tool (not shown) applied upon the nut-head 4, the nut 2 may be turned in a screwing or fastening direction 40 upon an interposed bolt, that is to say, in the direction opposite to that faced by the ratchet-shoulders n', the bolt 11 being successively depressed against the tension of spring 10 by the cam-faces n of the several notches 6 45 and the nut 2 riding thereover, the slot 18 being, as stated, of sufficient length or width to permit such successive depression of the bolt 11 when not key-actuated. On a key 16 being inserted in the casing 14 and the barrel 50 15 then rotated, the bolt 11 will be pulled by the crank-pin 17 and against the tension of the spring 10 out of engagement with the nut 2, when the nut 2 may be freely rotated in a so-called non-screwing, release, or unfastening 55 direction.

The spare rim and tire carrier C is of ring-formation and of a suitable diameter to receive therearound the particular spare-rim D and its supported tire E. The ring or carrier C is suitably fixed to and upon the auto-

mobile F by means of a suitable bracket G, and fixed at a leg or portion 30 upon the carrier C, is an angle-block or bracket H, the other leg or portion 31 thereof being presented upwardly and facing rearwardly, as 70 best seen in Figure 1. Suitably welded or otherwise fixed, as at 32, to the leg 31 of block H, is a rearwardly presented mounting-bolt 33.

The spare-rim D and tire E being mounted 75 on the carrier C, my new lock is then employed to retain the rim D and tire E against unauthorized removal, and in use and operation, the lock is disposed with relation to the upstanding portion 31 of the bracket H for 80 engagement at its nut 2 with the fixed bolt 33. The nut 2 is then rotated in a direction opposite to that faced by the ratchet-shoulders n' to threadedly engage the bolt 33, movement of the nut 2 in such direction being permitted without the interposition of a key 16. As the nut 2 is so actuated, and the lock as a whole consequently shifted toward the carrier C, rim D, and block H, the lock-member B is first hookwise engaged 85 at its extension 23 with the rim D and then flatwise abutted against the angle H, so that finally, under such actuation of the nut 2, the block B seats against, and the screw 27 is then wholly covered and concealed by, the 90 bracket H.

In such manner, the rim D and its tire E are rigidly locked to and upon the carrier C, release or unfastening movement of nut 2 being prevented by the engagement of bolt 11 with one or the other of its notches 6. On the bolt 11 being pulled out of engagement with the nut 2 by means of the crank-pin 17 on actuation thereof by an inserted key 16, the nut 2 may be reversely rotated and thereby unscrewed from the bolt 33, when the lock as a whole may be disengaged from the carrier-bracket H and rim D, and the rim D and its tire E freed for removal from the carrier C. 100

I may add that the locking-assembly is of such type that the key 16 may not be withdrawn from the barrel 15 when the pin 17 is in bolt unlocking position, with the result that, as an element of safety, the operator 115 is advised that, when the key 16 is removable, the ratchet-mechanism is in operative locking condition.

I may further add that the recess 24, screw-opening 26, and bolt-opening 29 provided in the lock-member D are preferably elongated to permit of some relative shifting of the member B in its attachment to the block A to adjustably engage different rim-formations, the hook-extension 23 having a relatively deep slot for rim-engagement and said hook-extension being so relatively shaped as to closely hug the rim and thereby prevent the insertion thereunder of a tool in an endeavor to pry the lock from the rim. 120 125 130

My lock may be readily commercially manufactured and has been found exceedingly efficient in the performance of its intended functions.

5 I am aware that changes in the form, construction, arrangement, and combination of the several parts of my new lock may be made and substituted for those herein shown and described without departing from the nature and principle of my invention.

10 Having thus described my invention, what I claim and desire to secure by Letters Patent is:

1. A spare-rim lock including, in combination, a block, a locking-nut permanently secured for rotation in the block and having a threaded recess for engagement with a mounting-bolt, said recess opening upon an end face of the block, a separate rim and carrier engaging-member mounted on and disposed over said end face of the block and having an opening registering with said recess, and means for separably securing the block upon said engaging member.

25 2. In combination with a carrier and a spare rim mounted on the carrier, the carrier having a mounting bracket and a bolt projecting from said bracket, of an apertured plate fitted upon said bolt and having engagement with the rim, a block, means for separably securing the block upon the plate, and a nut permanently secured for rotary movement in the block and rotarily engageable with said bolt.

35 3. In combination with a carrier and a spare rim mounted on the carrier, the carrier having a mounting bracket and a bolt projecting from said bracket, of an apertured plate fitted upon said bolt and over the bracket and having hookwise engagement with the rim, a block, means for separably securing the block upon the plate, a nut permanently secured for rotary movement in the block and engageable with said bolt, a bolt mounted for movement in the block and engageable with the nut for preventing reverse rotation thereof, and key actuatable means for effecting disengagement of the bolt from the barrel.

45 4. A spare tire lock including a spare-rim engaging plate-member adapted to fit upon a mounting-bracket and having an aperture for accommodating a mounting bolt, said plate-member also having a surface recess, a lock-assembly comprising a block fitting at an end face upon said plate-member and having a lug projecting into recess, and a screw projecting through the plate and engaging said lug for separably securing the block to the plate-member.

55 5. A spare tire lock including a spare-rim engaging plate-member adapted to fit upon a mounting-bracket and having an aperture for accommodating a mounting bolt, said

plate-member also having a surface recess and a slot through its wall opening into said recess, a lock-assembly comprising a block fitting at an end face upon said plate-member and having a lug projecting into said recess, and a screw removably projecting through said slot and engaging said lug for adjustably securing the block to the plate-member.

6. The combination of a rim clamp having a recess and a bolt opening therein, a removable locking block, a lug on said locking block for aligning said block with said rim clamp to operably receive a bolt through the rim clamp to lock a rim between said rim clamp and a carrier.

In testimony whereof, I have signed my name to this specification.

WALTER LEWIS HAWKINS.
